UNITED STATES PATENT OFFICE.

RAY GRIFFITH, OF SABETHA, KANSAS.

ROAD DRAG.

Application filed January 5, 1924. Serial No. 684,640.

To all whom it may concern:

Be it known that I, RAY GRIFFITH, a citizen of the United States, residing at Sabetha, in the county of Nemaha and State 5 of Kansas, have invented certain new and useful Improvements in Road Drags, of which the following is a specification.

The present invention relates to road scrapers or drags and particularly to an attachment therefor in the form of a movable blade cooperating with means whereby it may be placed in various positions in relation to one of the fixed blades or scrapers of the road drag or scraper.

Another important object of the invention is to generally improve upon structures of this nature by providing a device which is efficient and yet simple, one which is reliable, easy to manipulate, durable, 15 and well adapted to the purpose for which it is designed.

With the above and numerous other objects in view as will appear as the description progresses, the invention resides in certain novel features of construction, and in the combination and arrangement of parts as will be hereinafter more fully described and claimed.

In the drawing:

Figure 1 is a perspective view of a road drag embodying my invention;

Figure 2 is a detail view showing the ball and socket joint used therewith;

Figure 3 is a detail end elevation of the 35 attachment;

Figure 4 is a similar view showing the movable blade in a different position;

Figure 5 is a detail section taken substantially on the line 5—5 of Figure 3 looking 40 in the direction of the arrows; and

Figure 6 is an enlarged detail view showing the link connection between the crank and the movable blade supporting bar.

Referring to the drawing in detail it will 45 be seen that the road drag herein illustrated consists of a rear scraper A, a front scraper B substantially shorter than the rear scraper and connected thereto by the end beams 1 and 2 and the intermediate beam 3.

The end beam 2 is arranged diagonally of 50 the drag because of the fact that the forward scraper is shorter than the rear scraper. A suitable platform indicated at C is provided on the beams 1, 2 and 3. A

movable scraper or blade D is associated with the forward scraper B being connected to one end thereof by a ball and socket joint E, the socket portion 4 thereof being fixed to the movable scraper D and the ball 5 thereof being attached to the front scraper B adjacent one end. In end elevation the movable scraper D is curved as is indicated to advantage in Figures 3 and 4. A slotted plate 6 extends from one end of the rear scraper A and a bar 7 passes through the slot thereof. The forward end of this bar 7 is connected to one end of the blade D adjacent its bottom by means of an eye bolt 8 or in any other suitable manner. A crank 9 is journaled in a bracket 10 mounted intermediate the ends of the platform C and a bracket 11 at one end thereof so that a link 12 may be connected to the part 7 and to the arm 13 of the crank 9. The arm 14 is utilized for operating the crank so as to 75 actuate the link 12 thus lowering or raising the end of the bar 7 attached to the movable blade D and in order that the blade may be held in a desired position the bracket 10 is provided with a plurality of notches 16 80 on its arcuate edge adapted to be engaged by a dog on the arm 14.

In order to change the angle of the movable blade D, an arm 20 is pivoted at one end to the bar 7 as at 21 being operable by 85 an arm 22. The other end of the arm 20 is attached to the upper portion of the blade D by a link 23. Thus by moving the arm 22 the angle of the blade D may be varied as is indicated to advantage in Figures 3 90 and 4. A plate 24 is mounted on the bar 7 and provided with a notch edge of arcuate construction adapted to be associated with a dog indicated in dotted lines in Figure 3 so that the arm 22 may be held in a position 95 to retain the blade D in an adjusted angular relation to the ground. By moving the bar 7 through the slot of the plate 6 it will be seen that the angle between the blade D and the blade B may be varied. 100 This bar 7 is provided with a plurality of apertures 25 in order that a pin 26 or the like may be placed therein so as to abut the plate 6 and hold the blade D at a desired angle in relation to the blade B.

From the above description it is evident that the movable blade may be elevated at one end or partially rotated so as to vary its angle in relation to the ground and also moved so as to vary its angle in relation to 110

the blade or scraper to which it is attached by the ball and socket joint E. It is evident that numerous changes in the details of construction and in the combination and arrangement of parts may be resorted to without departing from the scope or spirit of the invention or sacrificing any of its advantages.

What is claimed is:

10. 1. In combination with a road drag including a fixed scraper, of a movable scraper and means whereby the movable scraper may be actuated to various angles in relation to the fixed scraper and at various angles in relation to the ground and also means whereby one end of the movable scraper may be elevated and lowered.
15. 2. In combination with a road drag, a fixed scraper, a movable scraper, a ball and socket joint between the fixed scraper and the movable scraper, means for actuating the movable scraper in different positions in relation to the fixed scraper.

3. In a road drag of the class described, a fixed blade, a movable blade, a ball and 25 socket joint between the blades, a slidably mounted bar on the road drag loosely connected to the movable blade whereby by sliding the bar the angle between the blades may be varied, and means whereby the end of the bar connected to the movable blade may be elevated, and means on the bar for varying the angle of the movable blade in relation to the ground.

4. In combination with a road drag, a 35 scraper, a ball and socket joint between the scraper and the road drag, and means for actuating the scraper in different positions in relation to the drag.

In testimony whereof I affix my signature in presence of two witnesses.

RAY GRIFFITH.
